UNITED STATES PATENT OFFICE

BERNICE E. LAMBERT, OF COLUMBUS, OHIO

MEANS FOR SEALING BURIAL CASES

Application filed December 20, 1928. Serial No. 327,455.

This invention relates broadly to improvements in sealing means and is particularly adapted to burial cases, caskets or vaults, although the scope and application of the invention are not, of course, limited to this specific field of employment, as the principles of the invention are applicable to receptacles embodying two separable sections employed for many other widely different uses and purposes.

One of the outstanding features of the present invention lies in the provision of a seal in the form of a compound which is carried by the upper edge of the casket or receptacle and which at the time of sealing can be put into a flowing state so as to automatically lock and hermetically seal the closure of the structure to be sealed.

Another important object is to provide the receptacle with a permanently carried sealing unit in the form of an electric resistance wire embedded in the sealing compound carried by the receptacle, and which heating unit may be energized by an outside source of electric current thereby heating and placing the compound in a flowing or softened state, so that the depending locking web carried by the lower edge of the cover section of the receptacle may be embedded in the compound.

Upon the subsequent cooling and hardening of the sealing compound, a secure union will exist between the sections of the receptacle. By the provision of this embedded heating unit the sealing compound may be softened and the cover section of the receptacle can be lifted off for the inspection of the interior of the receptacle.

It is also an object of the present invention to provide certain improvements in the form, construction and arrangement of parts whereby the above named and other objects may be effectively attained, hereinafter fully described and set forth in the appended claims.

In the accompanying drawings:

Figure 1 is a plan view of a receptacle constructed in accordance with the present invention, a portion thereof being broken away to disclose underlying structures,

Figure 2 is an enlarged vertical sectional view taken on the line 2-2 of Figure 1,

Figure 3 is a similar view showing a portion of the casket and its cover in position to be applied thereto,

Figure 4 is a vertical sectional view taken on the line 4-4 of Figure 2,

Figure 5 is a horizontal sectional view disclosing more particularly the electrical heating unit used in connection with the present invention,

Figure 6 represents a slightly modified form of sealing means,

Figure 7 is a sectional view taken on the line 7-7 of Figure 6.

Referring more particularly to the drawings, the numeral 1 designates a receptacle constructed in accordance with the features of the present invention. In the present instance the receptacle has been shown in the form of a burial case or casket, but, of course, I do not limit myself to this particular adaptation of the invention as the same may be applicable to other fields of employment. The case or receptacle is comprised broadly of a base section 2 and a separable cover section 3. The base section comprises the usual bottom, vertically upstanding side and end walls 5 and 6 and an open top. In this instance the upper edges of the walls 5 and 6 are welded, 70 braced or otherwise secured to an outwardly curving trim section 7, which extends around all four walls of the base section. The upper edge of the trim section includes an inwardly extending, substantially flat horizontal flange 8, which forms the seat for the cover section 85 of the casket. Formed in the flanges 8 of the section 7 is a continuous groove or channel 9, extending around the sides and end of the body portion of the casket. The groove 9 possesses in cross-section, a substantially keystone form, having a relatively restricted entrance slot 10 and a widened lower portion 11. The cover section 12 of the receptacle is provided with a continuous depending web 95 13, which is adapted to be received within the groove or channel 9 and has its extreme lower end provided with a relatively widened head 14, when embedded in the sealing compound, indicated at 15, will serve to lock the cover 100

section in secured relation and in a relative position with the base section 2.

The sealing compound is inserted in the groove 9, prior to the positioning of the cover into which compound the web 13 is securely embedded. In order to omit the handling of the sealing compound, which is preferably of a bituminous material, and to facilitate the sealing of the casket by the person attending this operation, the compound is poured into the groove and allowed to cool and harden before the casket or receptacle is shipped to the person who finally seals the same. During this shipment the cover section is supported in an elevated position as indicated in Figure 3 of the drawings, with the web 13 out of engagement with the compound 15. To effect the softening of the compound into a semi-plastic state so that the cover section may be put on the casket for the sealing thereof, there is embedded in the compound a wire or resistance element 16 which is supported and spaced from the sides and bottom of the groove 9 by means of spacers 17 formed from cardboard, fiber or other nonconducting material. The spacers 17 are shaped to conform with the sides of the groove 9 and are frictionally held in an upright position therein by engaging the sides of the groove thus forming a rigid support for the resistance element 16. The element 16 which lies within the groove 9 is positioned within openings 18 provided therefor in the spacer elements 17 and is inserted through slots provided in the upper edge of said spacers. This edge is also cut away as at 19 to accommodate the depending web 13 of the cover section. To convey electric current into the resistance element 16 there is provided in the side wall of the casket a plug 20 of the prong and socket construction with which the ends 21 of the wire 16 are connected and may be supplied with current from a convenient house circuit or from a storage battery and led through a conveying cable 22. Before shipping or handling the casket the exposed surface of the sealing compound may be painted or a strip of paper may be pasted over the entrance to the groove to prevent the sealing compound from running over the edge of the groove should the compound become soft during shipment of the casket and before the cover section thereof is put in place. The paper strip could be finished or formed of a material having the color harmonizing with the finish of the casket thus adding to the appearance and concealing the compound from view. As the paper is easily punctured by the locking web 13, there is no need of removing the same before sealing the casket.

In operation it will be understood that the cover section is placed on the base section with the web 13 resting on top of the hardened sealing compound which has been previously inserted into the groove 9. Then by

applying electric current to the heating element the compound becomes softened and the cover section, due to its weight, will gravitate until the same is resting upon the flange 8 of the body section, thus embedding the web 13 into the compound 15. The current is then shut off by disconnecting the plug 20 from the cable 22. The compound is then allowed to cool and harden, whereby, due to the peculiar formation of the groove 9 and the web 13, a locking condition is established preventing undue separation of the two sections of the receptacle. Moreover, due to the presence of the sealing compound, the interior of the receptacle will be, in effect, hermetically sealed, the elements excluded and the contents of the receptacle indefinitely preserved. If for any reason it is desired to open the receptacle after the same has been sealed, it is only necessary to apply electric current so as to heat or soften the compound, thereby breaking the locking hold of the seal.

In the modified form of the invention disclosed in Figures 6 and 7, the compound 15a with the heating element 16a, embedded therein, may be molded into separable sections which may be united and laid into the groove 9 of the casket and assembled therein. As the compound is in more or less of a semi-plastic state, the same may be bent to fit around the corners of the groove 9. The heating element 16a of each section is aligned to interfit with one another through the slip joint connection 23, formed at each end of the sections.

It is obvious that other modifications may be employed without departing from the principles of the invention as above set forth, and I therefore do not limit myself to such structural details, except as they may be specifically included in the following claims.

What is claimed is:

1. In a receptacle of the class described, a base having a continuous groove in its upper surface, a cover provided with a continuous depending web adapted to enter said groove, a sealing compound in the groove arranged to embed said web, upright spacers positioned within said groove throughout its length, and an electric heating element supported by said spacers.
2. In a receptacle of the class described, a base section having a continuous groove in its upper surface, a cover section provided with a continuous depending web on its under surface adapted to enter said groove, a sealing compound in the groove arranged to embed said web, spacers positioned within said groove and formed from insulating material, said spacers are shaped to conform with the formation of said groove and are frictionally held in an upright position, and an electric resistance element carried by said spacers and rigidly held within a recess formed therein, the ends of the resistance element

has an electric connection with the exterior of the receptacle.

3. In a receptacle of the class described, a base having a continuous groove in its upper surface, a cover provided with a continuous depending web adapted to enter said groove, a sealing compound in the groove arranged to embed said web, an electric heating element positioned in said groove and embedded within said compound, and means for insulatively supporting said element from the walls of said groove.

In testimony whereof I affix my signature.

BERNICE E. LAMBERT.
